ELECTRIC FORGING MACHINE

Grato Mora, London, England, assignor to Omes Limited, London, England, a British company

Application December 6, 1939, Serial No. 307,880
In Great Britain September 29, 1938

10 Claims.

(CL 219—3)

This application corresponds to the application of Grato Mora and Omes Limited, Serial No. 28,371/38, which was filed in Great Britain on September 29, 1938.

5 This invention comprises improvements in or relating to electric forging machines. Electric forging machines are well known in which a workpiece is electrically heated between electrodes and then deformed by mechanical pressure. For example work can be gripped in a vice which constitutes one electrode and pressed against an anvil which constitutes another electrode so that the work becomes heated between the vice and the anvil. Upsetting pressure then 15 being applied to the end of the work a head is formed between the vice and the anvil and if the work is free to slide through the jaws of the vice the head may be of great size relatively to the diameter of the workpiece. This process has not, 20 however, hitherto been adapted for economically dealing with small workpieces, especially when these are of cheap material.

According to the present invention in an electric forging machine there are provided in combination two sets of upsetting devices, each upsetting device including means for heating a workpiece electrically and hydraulic pressing means for applying upsetting pressure to the workpiece, and control means interlinking the 30 hydraulic pressing means constructed to cause the automatic alternate operation thereof. By this means the operator is enabled to place a workpiece or workpieces in one set of upsetting devices while a workpiece or workpieces is being 35 upset by the other set of devices and the output of the machine is increased. According to one construction according to the invention the cylinders of the hydraulic pressing means of one set are so connected by pressure fluid supply pipes 40 to the cylinders of the other set that when upsetting pressure is supplied to said one set withdrawal pressure is supplied to said other set and vice versa.

In a convenient arrangement the vice-electrodes and the anvil-electrodes are arranged one above the other and are disposed so as to occupy the front face of the machine considered as a whole so that the electrodes are readily accessible from the front of the machine, the transformer and the actuating devices for the electrodes being kept out of the way to the side or the rear, as this facilitates the quick insertion and removal of the parts.

One embodiment of electric forging machine 55 according to the invention will now be described

by way of example, reference being had to the accompanying drawings in which:

Figure 1 is a partly diagrammatic front elevation of the forging machine;

Figure 2 shows on an enlarged scale a control valve operating mechanism; and

Figure 3 is a detail sectional view on the line 3—3 of Figure 2 showing a releasable catch embodied in said valve operating mechanism.

The electric forging machine comprises a base 10 frame 1 on the front face of which are mounted two sets of upsetting devices carried on heavy shelves 2 secured to the base frame 1.

Each upsetting device comprises two hydraulic cylinders 3 for operating upsetting rams 4 which 15 project downwardly and operate crossheads 5 working on slides 6 arranged between the shelves 2 and carrying stops 7. Below the rams 4 and in line therewith there are arranged the electrodes. The lowest pair of electrodes 8 consists 20 of two anvil-electrodes which are connected to the terminals of the secondary winding 9 of a stepdown transformer. The secondary winding of the transformer is indicated diagrammatically and the transformer is located within the base 1 25 and is of conventional design. The anvil-electrodes are each provided with the usual water-cooling arrangements and with an anvil face 10 of special hard alloy of good electrical conductivity. The anvil faces 10 are at right angles to 30 the axes of the hydraulic cylinders which are above them. Above the anvil-electrodes 8 there are located a pair of vice-electrodes. The vice-electrodes consist of a pair of movable jaws 11 and 12, one for each anvil-electrode, which are 35 mounted on the base frame 1 to slide in a horizontal direction parallel to the front face of the frame. The other jaws 13 of the vice-electrode are constituted by a single block located between the jaws 11 and 12 and of such dimensions that 40 when two workpieces 14 are gripped between the fixed jaws 13 and the movable jaws 11 and 12, the workpieces 14 are held in line with the rams above and the anvils 10 below. The anvil-electrodes 8 are insulated from the frame and from 45 each other and the electrical circuit extends from one anvil-electrode 8 through one workpiece 14, block 13, the other workpiece 14 to the other anvil-electrode 8, the workpieces thus being in series one with another and receiving the same 50 heating current. The workpieces are engaged at their rear ends by the rams 4 and are thereby caused to slide through the vice-electrodes and be upset simultaneously when the workpieces have been heated. 55

The two vice jaws 11 are carried by hydraulic rams 15 which work in cylinders 16 bolted to the lower shelf 2, with its axis horizontal and parallel to the front face of the frame 4. The two vice jaws 12 are carried by a single ram 17 which works in a cylinder 18 disposed between the jaws so that when one vice jaw 12 is closed the other vice jaw 12 is open.

The hydraulic pressure supply pipe system connecting the various cylinders will now be described. The upper ends of the cylinders 3 of each set are connected by pipes 19 and their lower ends by pipes 20. The pipe 19 of each set of upsetting devices is connected by a pipe 21 to the pipe 20 of the other set of upsetting devices. Thus when one pair of rams 4 are making an upsetting stroke the other pair of rams 4 are being moved upwardly to prepare for a further upsetting stroke.

20 The outer portion of the left-hand cylinder 16 is connected by a supply pipe 22 to the right-hand portion of the central cylinder 18 and to the inner portion of the right-hand cylinder 16, while the outer portion of right-hand cylinder 16, 25 16 is connected by a supply pipe 23 to the left-hand end of the central cylinder 18 and the inner end of the left-hand cylinder 16. Thus when the jaws of the left-hand pair of vice-electrodes are closed the jaws of the right hand pair of 30 vice-electrodes are open.

A supply pipe 24 connects the supply pipe 22 to the supply pipe 21 leading to the upper end of the left-hand pair of ram cylinders 3 and a supply pipe 25 connects the supply pipe 23 to the pipe 21 leading to the upper ends of the right-hand pair of ram cylinders 3. Thus when the left-hand pair of rams are making an upsetting stroke, the left-hand pair of vice-electrodes are clamped on the workpieces and the 40 other vice-electrodes are open to permit the insertion of fresh workpieces.

The supply pipes 24 and 25 are further connected to a hydraulic valve 26 to which supply pipes 27, 28 leading respectively to a pressure 45 pump 29 and sump 30 are also joined. The pump 29 and sump 30 are accommodated within the base frame of the machine and are of conventional design; these parts have therefore been indicated diagrammatically. Thus a single hydraulic valve may be employed for reversing the 50 direction of motion of the rams in the cylinders 3, 16, 18.

The valve 26 is operated by a pivoted lever 31 from the cross-heads 5, the mechanism for carrying out the reversing operation being shown in detail in Figures 2 and 3.

Pivoted to uprights 40 secured to the upper shelf 2 there are a pair of levers 41, the outer ends of which are connected by rods 52 to one 60 of the cross-heads 5 of one or other set of upsetting devices. Thus the right-hand lever 41 is connected to a cross-head of the right-hand set of upsetting devices and the left-hand lever 41 to a cross-head of the left-hand set of upsetting devices.

The inner end of each lever 41 is connected by a spring 42 and an eye-bolt 43 which passes through a hole in the lever 31 and carries at its free end adjusting and lock nuts 44.

70 A pair of bell-crank levers 45 forming releasable catches are also pivoted to the frame members 40. One arm 45a of each bell-crank lever 45 is notched and is located so that the notch engages an arm of the lever 31. The other arm 75 45b of the bell-crank lever 45 is connected by

a spring 46 to the frame member 40 so as to be urged towards the lever 31 and is provided with an eye through which passes a rod 47 carrying a stop 48 at one end and connected to the lever 41 at the other end.

The operation of the valve is effected as follows:

As the cross-head 5 of a ram descends on its upsetting stroke (with the parts as shown in Figure 2 the left-hand pair of rams would be 10 descending), the rod 52 is drawn downwardly causing a rotation of lever 41, the placing of the spring 42 under tension and the raising of rod 47. The lever 31 cannot tilt, however, due to the releasable catch 45 being in engagement therewith. When the ram reaches the end of its upsetting stroke, the stop 48 presses against the arm 45b and causes the bell-crank lever 45 to rock thereby to disengage the notched arm 45a from the lever 31, whereupon due to the 20 tension in the spring 42 an arm of the lever 31 is raised to operate the valve 26. It will be appreciated that the spring 42 connected to the other arm of the lever 31 and to the other set of upsetting devices does not oppose operation 25 of the valve since the rams to which it is connected have been withdrawn to the top of the stroke and the spring 42 is therefore slack. It will be seen that the mechanism for operating the valve 26 is automatically tripped by the arrival of the cross-heads on the right-hand side or left-hand side of the machine at a predetermined tripping position which represents the end of the corresponding upsetting stroke. Therefore, when the rams on the left-hand side of the machine have fully upset two workpieces the valve 26 will be tripped so as to release the corresponding vises and to commence a withdrawal stroke and at the same time to initiate the upsetting strokes of the right-hand rams and to 40 clamp the corresponding vice-electrodes on the workpieces, and vice versa. In this way the operator has no other labour to perform than that of removing the completed workpieces when they have been upset and inserting fresh ones. 45 This machine can economically effect upsetting operations in the manufacture of bolts, motor-car valves and like parts which need to be produced quickly and in large numbers.

Conveniently the axis of the upsetting apparatus inclines rearwardly from the vertical at an angle of somewhat less than 10° as this helps the workpieces to remain in place in the machine when inserted by the operator until the vise jaws close upon them.

I claim:

1. In an electric forging machine, the combination of two sets of upsetting devices, each upsetting device comprising electric heating means 60 for heating a workpiece and hydraulic pressing means including hydraulic cylinders for applying upsetting pressure to the said workpiece, means to supply pressure fluid to the hydraulic cylinders, pressure fluid supply pipes connecting the hydraulic cylinders of one set of upsetting devices to the hydraulic cylinders of the other set so that when upsetting pressure is supplied to the cylinders of said one set withdrawal pressure is supplied to the cylinders of the other set and vice versa, control valve means in the said supply pipes, tappet means for each of the hydraulic pressing means which are engaged by said pressing means at the termination of its working stroke, each of said tappet means being operatively connected to said valve means to open the 70 75 80 85 90 95 98

hydraulic connection of the hydraulic pressing means of the other set from that of the tappet so actuated whereby automatic alternate operation of the upsetting devices is secured.

5. 2. In an electric forging machine, the combination of two sets of upsetting devices, each upsetting device comprising electrical heating means for heating a work-piece and hydraulic rams for applying upsetting pressure to the work-pieces, means to supply pressure fluid to the hydraulic rams and control means interlinking the hydraulic rams constructed to cause the automatic alternate operation of the upsetting devices, said control means including valve means controlling the supply of pressure fluid to the rams and means for actuating the valve means operated by the sets of upsetting devices alternately at the completion of the upsetting strokes of the rams so as to initiate the upsetting strokes of the rams of the other set of upsetting devices.
3. In an electric forging machine, the combination of two sets of upsetting devices, each upsetting device comprising electrical heating means for heating a workpiece and hydraulic rams for applying upsetting pressure to the work-pieces, means to supply pressure fluid to the hydraulic rams, pressure fluid supply pipes connecting the rams of one set of upsetting devices to the rams of the other set of upsetting devices so that when upsetting pressure is supplied to the rams of one set withdrawal pressure is supplied to the rams of said other set and vice versa, and control means interlinking the hydraulic rams constructed to cause the automatic alternate operation thereof, said control means including valve means controlling the supply of pressure fluid to the rams, and means for actuating the valve means operated by the sets of upsetting devices at the completion of the upsetting strokes of the rams so as to initiate the upsetting strokes of the rams of the other set of upsetting rams.
4. In an electric forging machine, the combination of two sets of upsetting devices, each upsetting device comprising hydraulic pressing means for applying upsetting pressure to a workpiece and electrical heating means for heating the workpiece including hydraulically-operated vice-electrodes for gripping the workpiece during the upsetting stroke, means including fluid-pressure supply-pipes to supply pressure fluid to the hydraulic pressing means and to the hydraulically-operated vice-electrodes, control valve means in the said supply pipes, tappet means for each of the hydraulic pressing means which are engaged by said pressing means at the termination of its working stroke, each of said tappet means being operatively connected to said valve means to change the hydraulic connection of the hydraulic pressing means and of the vice electrode of the other set of upsetting devices from that of the tappet so actuated as to cause the alternate automatic operation of the hydraulic pressing means and to cause the corresponding vice-electrodes to apply gripping force to the workpiece when the hydraulic pressing means apply upsetting pressure and release said force when the upsetting pressure is released.
5. In an electric forging machine, the combination of two sets of upsetting devices, each upsetting device comprising hydraulic pressing means for applying upsetting pressure to a workpiece and electrical heating means for heating the workpiece including hydraulically-operated vice-electrodes for gripping the workpiece dur-

ing the upsetting strokes, means including fluid-pressure supply-pipes to supply pressure fluid to the hydraulic pressing means and to the hydraulically-operated vice-electrodes, said pressure fluid supply pipes connecting the cylinders of the hydraulic pressing means and the hydraulically-operated vice-electrodes of one set to the hydraulic pressing means and hydraulically-operated vice-electrodes of the other set so that when upsetting pressure and gripping pressure is supplied to one set withdrawal and releasing pressure is supplied to the other set and vice versa, control valve means in the said supply pipes, tappet means for each of the hydraulic pressing means which are engaged by said pressing means at the termination of its working stroke, each of said tappet means being operatively connected to said valve means to open the hydraulic connection of the hydraulic pressing means of the other set from that of the tappet so actuated whereby automatic alternate operation of the upsetting devices is secured.

6. In an electric forging machine, the combination of two sets of upsetting devices, each upsetting device comprising electrical heating means for heating a workpiece and hydraulic pressing means for applying upsetting pressure to the said workpiece, means to supply pressure fluid to the hydraulic pressing means and control means interlinking the hydraulic pressing means of the pair of upsetting devices and constructed to cause automatic alternate operation of the upsetting devices, said control means including a reversing valve adapted alternately to connect the sets of upsetting devices to the pressure fluid supply, a pivoted lever for operating the valve, resilient connections joining said pivoted lever to the hydraulic pressing means in such a manner that the resilient connections are brought under stress during the upsetting stroke of the upsetting devices to which they are joined, releasable catches adapted to prevent the operation of the valve by the lever under the action of the stressed resilient connections and means connecting the releasable catches to the hydraulic pressing means to release said catches at the end of their upsetting strokes thereby to permit operation of the valve.

7. In an electric forging machine, the combination of two sets of upsetting devices, each upsetting device comprising electric heating means for heating a workpiece and hydraulic pressing means including cylinders for applying upsetting pressure to the said workpiece, means to supply pressure fluid to the hydraulic pressing means, pressure fluid supply pipes connecting the cylinders of one set of upsetting devices to the cylinders of the other set so that when upsetting pressure is supplied to said one set withdrawal pressure is supplied to the other set and vice versa, and control means interlinking the hydraulic pressing means of the sets of upsetting devices and constructed to cause automatic alternate operation of the upsetting devices, said control means including a reversing valve adapted alternately to connect the upsetting devices to the pressure fluid supply, a pivoted lever for operating the valve, resilient connections joining said pivoted lever to the hydraulic pressing means in such a manner that the resilient connections are brought under stress during the upsetting stroke of the upsetting devices to which they are joined, releasable catches adapted to prevent the operation of the valve by the lever under the action of the stressed resilient connections and means con-

necting the releasable catches to the hydraulic pressing means to release said catches at the end of their upsetting strokes thereby to permit operation of the valve.

- 5 8. In an electric forging machine, the combination of two sets of upsetting devices, each upsetting device comprising hydraulic pressing means for applying upsetting pressure to a work-piece and electrical heating means for heating 10 the workpiece including hydraulically-operated vice-electrodes for gripping the workpiece during the upsetting strokes, means to supply pressure fluid to the hydraulic pressing means and to the hydraulically-operated vice-electrodes, and control 15 means interlinking the hydraulic pressing means and the vice-electrodes of the sets of upsetting devices, said control means being constructed to cause the alternate automatic operation of the upsetting devices and to cause the 20 vice-electrodes to apply gripping force to the workpiece when the corresponding hydraulic pressing means apply upsetting pressure to said workpiece and to release said gripping force when the upsetting pressure is released and said control 25 means including a reversing valve adapted alternately to connect the hydraulic pressing means and the vice-electrodes of the sets of upsetting devices to the pressure fluid supply, a pivoted lever for operating the valve, resilient connections joining said pivoted lever to the hydraulic 30 pressing means in such a manner that the resilient connections are brought under stress during the upsetting strokes of said hydraulic pressing means, releasable catches adapted to 35 prevent the operation of the valve by the lever under the action of the stressed resilient connections and means connecting the releasable catches to the hydraulic pressing means to release said catches at the end of their upsetting strokes thereby to permit operation of the valve.
- 40 9. In an electric forging machine, the combination of two sets of upsetting devices, each upsetting device comprising a plurality of anvil-electrodes, hydraulically-operated vice-electrodes for gripping workpieces arranged above each of 45 said anvil-electrodes, said anvil-electrodes and said vice-electrodes being arranged so that workpieces disposed therebetween are electrically in series, means to supply electric current to said electrodes for heating said workpieces and hydraulic rams above said electrodes and in line therewith adapted to apply upsetting pressure to the heated workpieces, the cylinders of the hydraulic rams of each set being connected to the 50 cylinders of the vice-electrodes so that the vice-electrodes grip the workpieces when upsetting pressure is applied thereto and release the workpieces when the upsetting pressure is released, means for supplying pressure fluid to the hydraulic rams and the hydraulically-operated vice-electrodes of one set of upsetting devices to the hydraulic rams and hydraulically-operated vice-electrodes 55 of the other set of upsetting devices so that when upsetting and gripping pressure is supplied to the cylinders of one set, withdrawal and release pressure is supplied to the cylinders of the other set, and control means interlinking the sets of upsetting devices and constructed to cause the alternate automatic operation of the upsetting devices, said control means comprising a reversing valve adapted alternately to connect the upsetting devices to the pressure fluid supply, a pivoted lever for operating the valve, resilient connections joining said pivoted lever to the hydraulic rams in such a manner that the resilient connections are brought under stress during the upsetting stroke of the upsetting devices to which they are joined, releasable catches adapted to prevent the operation of the valve by the lever under the action of the stressed resilient connections and means connecting the releasable catches to the hydraulic rams to release said catches at the end of their upsetting strokes thereby to permit operation of the valve.

the hydraulic rams and hydraulically-operated vice-electrodes of the other set of upsetting devices so that when upsetting and gripping pressure is supplied to the cylinders of one set, withdrawal and release pressure is supplied to the cylinders of the other set, and control means interlinking the sets of upsetting devices and constructed to cause the alternate automatic operation of the upsetting devices, said control means including valve means controlling the supply of 1 pressure fluid to the rams and vice-electrodes, said valve means being actuated by the sets of upsetting devices alternately at completion of their upsetting strokes so as to initiate the upsetting strokes of the rams of the other set of 1 upsetting devices.

10. In an electric forging machine, the combination of two sets of upsetting devices, each upsetting device comprising a plurality of anvil-electrodes, hydraulically-operated vice-electrodes 2 for gripping workpieces arranged above each of said anvil-electrodes, said anvil-electrodes and said vice-electrodes being arranged so that workpieces disposed therebetween are electrically in series, means to supply electric current to said electrodes for heating said workpieces and hydraulic rams above said electrodes and in line therewith adapted to apply upsetting pressure to the heated workpieces, the cylinders of hydraulic rams of each set being connected to the cylinders 30 of the vice-electrodes so that the vice-electrodes grip the workpieces when upsetting pressure is applied thereto and release the workpieces when the upsetting pressure is released, means for supplying pressure fluid to the hydraulic rams and the hydraulically-operated vice-electrodes, supply pipes connecting the cylinders of the hydraulic rams and hydraulically-operated vice-electrodes of one set of upsetting devices to the hydraulic rams and hydraulically-operated vice-electrodes 40 of the other set of upsetting devices so that when upsetting and gripping pressure is supplied to the cylinders of one set, withdrawal and release pressure is supplied to the cylinders of the other set, and control means interlinking the sets of upsetting devices and constructed to cause the alternate automatic operation of the upsetting devices, said control means comprising a reversing valve adapted alternately to connect the upsetting devices to the pressure fluid supply, a pivoted lever for operating the valve, resilient connections joining said pivoted lever to the hydraulic rams in such a manner that the resilient connections are brought under stress during the upsetting stroke of the upsetting devices to which they are joined, 45 releasable catches adapted to prevent the operation of the valve by the lever under the action of the stressed resilient connections and means connecting the releasable catches to the hydraulic rams to release said catches at the end of their upsetting strokes thereby to permit operation of the valve.

GRATO MORA.
